The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

UNITED STATES PATENT OFFICE

2,539,512

TUBULAR GAS BURNER WITH ATTACHED REFLECTOR

William Charles Herbert, Brooklyn, and
William C. Herbert, Jr., Freeport, N. Y.

Application November 15, 1946, Serial No. 710,035

3 Claims. (Cl. 126—85)

1. This invention is an improvement in driers,

especially driers of the kind that employ direct heat to evaporate the moisture in the objects that are treated.

An important object of the invention is to provide a drier comprising an elongated burner with a reflector in position to throw the heat rays from the burner upon any article or series of articles in motion past the burner or held beneath it, and means for mounting the drier so that it can be easily shifted into and out of operative position.

The invention is particularly adapted for use with printing presses of the small cylinder type which deliver the paper in the form of sheets of greater or less size; but it may also be employed with other apparatus in connection with which a drier is needed. The drier is placed near the paper and all moisture is expelled from the ink thereon.

The nature and advantages of the invention are set out in the following specification but this disclosure is by way of explanation only; and various changes may be incorporated to the full extent of the meaning of the general terms in which the appended claims are expressed.

In the drawings:

Figure 1 is a cross section of a drier according to this invention.

Figure 2 is an end view.

Figure 3 shows a section on the line 3—3 of Figure 1, and

Figures 4 and 5 present details of the invention.

The numeral 1 indicates a swinging arm having at one end a couple of perforated bearing lugs 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

In the top of the arm 1 is a hollow member 7 in the form of a casing, which encloses a mixing chamber, and is screwed tightly to a tubular element or section of externally threaded piping 8, fixed in the arm 1. The short length of piping or tubing 8 extends through the arm, and on the other end is screwed fast a branched or T coupling 9, having its lateral branch 10 connected to a gas supply conduit 11. The end in

16 21 SWINGING ARM 1 having at one end a couple of 26 31 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

17 22 SWINGING ARM 1 having at one end a couple of 27 32 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

18 23 SWINGING ARM 1 having at one end a couple of 28 33 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

19 24 SWINGING ARM 1 having at one end a couple of 29 34 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

20 25 SWINGING ARM 1 having at one end a couple of 30 35 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

21 26 SWINGING ARM 1 having at one end a couple of 31 36 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

22 27 SWINGING ARM 1 having at one end a couple of 32 37 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

23 28 SWINGING ARM 1 having at one end a couple of 33 38 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

24 29 SWINGING ARM 1 having at one end a couple of 34 39 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

25 30 SWINGING ARM 1 having at one end a couple of 35 40 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

26 31 SWINGING ARM 1 having at one end a couple of 36 41 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

27 32 SWINGING ARM 1 having at one end a couple of 37 42 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

28 33 SWINGING ARM 1 having at one end a couple of 38 43 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

29 34 SWINGING ARM 1 having at one end a couple of 39 44 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

30 35 SWINGING ARM 1 having at one end a couple of 40 45 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

31 36 SWINGING ARM 1 having at one end a couple of 41 46 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

32 37 SWINGING ARM 1 having at one end a couple of 42 47 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

33 38 SWINGING ARM 1 having at one end a couple of 43 48 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

34 39 SWINGING ARM 1 having at one end a couple of 44 49 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

35 40 SWINGING ARM 1 having at one end a couple of 45 50 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

36 41 SWINGING ARM 1 having at one end a couple of 46 51 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

37 42 SWINGING ARM 1 having at one end a couple of 47 52 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

38 43 SWINGING ARM 1 having at one end a couple of 48 53 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

39 44 SWINGING ARM 1 having at one end a couple of 49 54 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

40 45 SWINGING ARM 1 having at one end a couple of 50 55 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

41 46 SWINGING ARM 1 having at one end a couple of 51 56 PERFORATED BEARING LUGS 2, so that the arm can be mounted on a stud or journal 3, supported by the framework of the machine for which the drier is intended. The arm extends upward from the journal 3, and supports in horizontal position a tube 4 having a row of burner openings 5 along each side of the bottom. Over the burner pipe is a long, laterally curved reflector 6, which directs the heat downward. The arm can be moved horizontally on the journal 3.

20 The tube 4 is threaded into the casing 1, and is made fast thereto by means of a binding screw 17. The reflector 6 is mounted on two semicircular plates or heads; one of which, 18, is adjacent the casing 1, and has a central flanged bearing opening 19 for the tube 4. The other head 20 has a hollow boss 21 on its inner face to receive the outer end of the burner tube that is plugged shut at this point; and screws 22 make these heads fast on the tube 4. The heads 18 and 20 are connected by tie rods 23, with ends entering hollow bosses 24 on the inner faces of the heads 18 and 20. The ends have inside holes and are engaged and held fast by screws 25. The rods 23 have longitudinal recesses 26 and the bosses 24 have registering notches into which the side edges of the reflector 6 are inserted. The curved ends of the reflector are overlapped by marginal flanges 27 of the heads 18 and 20, and these ends engage both heads snugly. When the reflector is thus mounted between the heads and the rods are fixed in place by screws 25, the reflector 6 is held securely in place.

The heater is especially adapted for printing presses of the small cylinder type press known

by the name of "Little Giant," and others of the

same description, and when the press or other

machine is running, the paper is drawn past underneat the drier and any moisture at once dis-

appears. The burner pipe and reflector shield

then extend across the web or sheet; and when

the press is not running, the flames are extin-

guished and the drier can be swung to one side,

pivoting around the journal or stud 3.

The part of the press on which the drier unit

is mounted is shown at 28. The journal 3 is

screwed through this part and is held fast by a nut 29 engaging a shoulder 3 on the stud above the part 28, and a second nut 31 below. The lower lug 2 of the arm 1 has a recess 32 larger than the nut 29 and receiving the latter, leaving the arm 1 free to be moved as required.

The gas conduit 11 is preferably in the form of a flexible tube which extends from the coupling 9 to a valve casing 33 supported on a bracket 34 which is attached in any suitable way to a projection 35 on the framework 28. This casing contains a valve which is actuated by a solenoid and contains passages to control communication between a gas supply pipe 36 and the outlet to which the gas tube 11 is attached. The solenoid coil and the valve inside the casing 33 are not shown, but the wire conductors which supply current to the solenoid coil are indicated at 37. The casing has an outlet fitting 38 containing a regulating screw 39 and connected by a piece or section of tubing 40 to the tubing 16 to carry gas to the pilot flame adjacent the burner openings 5 in the tube 4. When the solenoid is energized by current flowing into it through the conductors 37 the valve is opened so that gas can flow from the intake conduit 36 to the tubing 11, but the outlet in the fitting 38 is always open for gas to flow by way of the section of tubing 40 to the pilot flame tubing 16. The latter tubing 16 is disposed inside of the tubing 11 up to a point near the coupling 9 where it emerges and passes through the casing 7 into the tube 4 and out at the point shown in Figure 1. The wires 37 are preferably part of the circuit of the electrical apparatus which operates the printing press. As soon as the current is turned on to set the press in motion, the valve in the casing 33 is open so the gas can flow through the conduit 11 to the casing 7 of tube 4. The gas issuing from the end of the tube 16 adjacent the tube 4 is then lighted immediately to make the burner ready for operation. The burner can then be swung into position over the sheets to be treated and as long as the press operates, the valve in the casing 33 is held open. When the current is cut off from the machine operating the press the solenoid in the casing 33 is deenergized, the valve then closes and the flow of gas to the tubing 11 is stopped; but the pilot flame at the end of the tubing continues burning. The pipe 40 could be connected directly between the conduits 11 and 36 with the regulator screw mounted therein.

The opening in the fitting 38 controlled by the screw 39 communicates with the space inside the casing 33 which is not closed by the valve between the supply pipe 36 and the outlet of the casing 33 to which the tubing 11 is attached. Hence the pilot tubing always supplies gas through the tubing to the pilot flame in the tube 4. The arrangement is similar to the design of the conventional gas range in which the tube

at the end of which the pilot flame burns is always in communication with the main gas pipe and this tube is not controlled by the shut off valve or valves which admit gas to the principal burners. Thus the pilot flame burns continuously even when the range is not in use.

Having described our invention, what we claim to be new is:

1. A combined heater and drier comprising a bent arm having means at one end to engage a support, a short length of tubing supported by the opposite end, a coupling being connected to a fuel supply conduit and carrying a valve in line with said tubing, a member enclosing a mixing chamber attached to the other end of said tubing, a gas burner tube connected with said member, a head supported by said burner tube adjacent said member, another head engaging the other end of the burner tube, connector rods joining the said heads, and means for holding said rods in position, the rods having grooves therein, and a reflector arched over the tube and having its longitudinal edges received in said grooves, the heads having peripheral flanges overlapping the ends of said reflector.

2. A combined burner and drier comprising an arm having bearing means, a mixing member on said arm, a fuel supply conduit and a valve operatively associated with said member, a burner tube attached to said member, heads on said tube, a reflector between said heads and arched over the tube and tie rods uniting said heads, the latter having peripheral flanges overlapping the ends of the reflector, and the rods having recesses for the side edges of said reflector.

3. A combined heater and drier comprising an arm having bearings for mounting it upon a journal, a heater tube and reflector shield horizontally supported at the other end of said arm, a valve casing supported adjacent the journal of said arm, a fuel intake conduit connected to said casing, a fuel conduit leading from said casing to said heater tube, said casing having a pilot tube outlet, tubing leading from said outlet into said conduit between the casing and the heater tube, said pilot tubing extending into the heater and terminating adjacent the heater tube, and means at said outlet for controlling the flow of fuel through the pilot tubing.
